(57) **CLAIM**

The ornamental design for a cup, as shown and described.

DESCRIPTION

FIG. 1 is a top, front, perspective view of a cup showing a first embodiment of our new design;

FIG. 2 is a bottom, rear, perspective view thereof;

FIG. 3 is a front view thereof, the rear view being a mirror image of the front view;

FIG. 4 is a right side view thereof, the left side view being a mirror image of the right side view;

FIG. 5 is a top view thereof; and

FIG. 6 is a bottom view thereof.

FIG. 7 is a top front perspective view thereof additionally showing environmental structure in penguin head shape;

FIG. 8 is a bottom, rear, perspective view thereof;

FIG. 9 is a front view thereof;

FIG. 10 is a rear view thereof;

FIG. 11 is a right side view thereof, the left side view being a mirror image of the right side view;

FIG. 12 is a top view thereof; and

FIG. 13 is a bottom view thereof.

FIG. 14 is a top front perspective view thereof additionally showing environmental structure in snowman head shape;

FIG. 15 is a bottom, rear, perspective view thereof;

FIG. 16 is a front view thereof;

FIG. 17 is a rear view thereof;

FIG. 18 is a right side view thereof;

FIG. 19 is a left side view thereof;

FIG. 20 is a top view thereof; and

FIG. 21 is a bottom view thereof.

FIG. 22 is a top front perspective view thereof additionally showing environmental structure in Santa head shape;

FIG. 23 is a bottom, rear, perspective view thereof;

FIG. 24 is a front view thereof;

FIG. 25 is a rear view thereof;

FIG. 26 is a right side view thereof;

FIG. 27 is a left side view thereof;

FIG. 28 is a top view thereof; and,

FIG. 29 is a bottom view thereof.

The features shown in broken lines depict environmental subject matter only and form no part of the claimed design. The bolded dash-dot broken lines indicate the bounds of the claimed subject matter.
